Primary Examiner — Kevin K Rudzinski*Assistant Examiner* — J. Thorn, Sr.(74) *Attorney, Agent, or Firm* — LOEB & LOEB LLP(57) **CLAIM**

The ornamental design for a hooded sweatshirt as shown and described.

DESCRIPTION

The sole DRAWING is a left side elevational view of a hooded sweatshirt showing my new design.

The broken lines depict portions of the hooded sweatshirt that form no part of the claimed design. The broken lines showing the drawstrings, seams, and stitching form no part of the claim.

1 Claim, 1 Drawing Sheet(56)
